UNITED STATES PATENT OFFICE.

OSCAR WALTER BRZAZOWSKY AND EVERETT McWILLIAMS, OF ALPENA, SOUTH DAKOTA.

DOOR ATTACHMENT FOR SHELLING-MACHINE HOPPERS.

Application filed May 6, 1922. Serial No. 558,935.

To all whom it may concern:

Be it known that we, OSCAR W. BRZAZOWSKY and EVERETT McWILLIAMS, citizens of the United States, residing at Alpena, in the 5 county of Jerauld and State of South Dakota, have invented certain new and useful Improvements in Door Attachments for Shelling-Machine Hoppers, of which the following is a specification, reference being had 10 to the accompanying drawings.

Very often in shelling corn and other grain, stones, sticks and other foreign matter are fed through the sheller with the grain. When such foreign matter reaches 15 the end of the feed auger or screw (not shown), it very often clogs the passage of the grain, causing pressure against the sides of the casing. Very often the screw is prevented from turning due to its clogging or 20 jamming, causing breakage of the parts, and as previously stated prevents the passage of the grain.

In order to relieve this clogging and the retarding of the passage of the grain and to 25 prevent breakage of parts, it is the purpose of the present invention to provide a door including means at the top of the door to retain the upper part of the door in position, and a break pin at the lower part of the door 30 to retain the lower part of the door in place. In this case the pressure of the foreign matter in the casing of the shelling machine and the pressure of the grain is urged against the inner face of the door, and when this 35 pressure upon the inner face of the door becomes great enough, the break pin will sever, hence releasing the lower portion of the door, said door being urged outwardly, and when its lower portion is moved far 40 enough, the upper part of the door will automatically release and hence permit the door to fall from the door opening.

Still another purpose is to provide a releasable door for a casing of a shelling machine provided with extensions at its top for engagement with a pair of keepers, and a single extension at the bottom provided with an opening, through which and through a flange of a casting of said casing a break pin 45 may extend, so that when sufficient pressure is exerted against the inner face of the door, the break pin will snap and allow the door to push outwardly at the bottom, whereby the extensions at the top may withdraw from 50 the keepers, and thereby entirely release the

door, thereby relieving the pressure on the interior of the casing, and enabling the feed auger or screw (not shown) to again operate.

It is to be understood that the particulars herein given are in no way limitative and that while still keeping within the scope of the invention, any desired modifications of detail and desired proportions may be made in the apparatus according to circumstances.

The invention comprises further features and combination of parts, as will be herein-after set forth, shown in the drawings and claimed.

In the drawings:

Figure 1 is a view in side elevation of a 70 corn or other grain shelling machine, preferably the right hand side thereof, showing the improved door as secured to the casting of the side of the hopper with the break pin inserted;

Figure 2 is a sectional view on line 2-2 of Figure 1, through one side of the hopper, showing the door in position and the break pin applied;

Figure 3 is an enlarged detail view of the 80 casting of the side of the hopper, showing the door in position;

Figure 4 is a detail view of the door;

Figure 5 is a detail perspective view of the reinforcing bar 5.

Referring to the drawings, 1 designates the casing in which the feed auger or screw (not shown) may be mounted, and adjacent one end thereof a casting 2 is bolted or otherwise fastened as at 3. This casting is located preferably on the right hand side of the hopper 4 of the corn or other grain shell- 90 ing machine, there being a reinforcing bar 5 bolted to the upper flange of the casting 2, to assist in holding the safety door 6 in position in the opening 7 of the casting.

The reinforcing bar 5 adjacent its inner edge is provided with a pair of elongated notches or recesses 8 and 9. Secured to the door 6, by means of bolts or rivets preferably the latter 10 is a bar 11, the upper end of which engages in the elongated notch or recess 8 of the reinforcing bar. The lower end of the bar 11 terminates in an ear or lug 12, which extends laterally at right angles to the bar 11, and is provided with an opening or aperture 13, which registers with the opening or aperture 14 in the lower flange of the casting 2 of the side of the hopper. A suitable holding break pin 15 engages 110

through the registering apertures 13 and 14, to hold the lower end of the bar 11 in position, and thereby assisting materially in holding the door 6 in the opening 7 of said casting.

In order to insure holding the door 6 in the opening 7 an additional reinforcing bar 16 is riveted or bolted at 17 to the door. The lower end of the reinforcing bar 16 is secured to the bar 11 by the lower rivet or bolt, which holds the bar 11 to the door. In order that the upper end of the bar 11 may engage the elongated notch or recess 8, it is extended beyond the upper edge of the door. The bar 16 is also extended beyond one edge and above the upper edge of the door, and is slightly curved at its upper end to engage the other elongated recess or notch 9 of said reinforcing bar 5, which acts to hold the door 20 securely in position.

Obviously should there be any foreign matter, such as stones and the like in the corn or other grain when being fed into the hopper of the sheller, it will create pressure on the inner face of the door 6 to such an extent as to cause the break pin 15 to break, then the pressure on the inner face of the door will cause the lower end of the door to move from engagement with the door opening, and when the lower end of the bar 11 is forced beyond the outer edge of the lower flange of the casting 2, the upper ends of the bars 11 and 16 will withdraw from the notches or recesses 8 and 9, and permit the door to fall from its position in the opening, thus allowing the escape of the foreign matter. In fact the foreign matter may become partly fed through the auger or screw, and then cause a stoppage in the operation of the feed screw, or the foreign matter such as stones may jam in the under portion of the feed screw or auger, and while the screw may continue turning, the grain will not pass through, and therefore will jam, and when this is the case the grain, such as corn or the like coming thereafter will cause pressure on the door, resulting in the breaking of the pin and releasing the door, allowing the escape of the grain. While the sheller may continue in its operation, in so far as the power remaining on is concerned, the various parts of the machine, such as the feed screw or auger may stop, allowing the operator to insert the hand or an instrument or tool, in order to relieve the jamming of the screw. After this is accomplished, the door may be replaced, a new break pin inserted, and the machine allowed to continue in its work of shelling corn or other grain.

The invention having been set forth, what is claimed is:—

1. The combination with the side of a passage through which material is forced, including the casting having a door open-

ing; of a door fitting said opening, said door having means at its upper end operatively and detachably connecting with the casting to assist in holding the door in position in the opening, and means operatively holding the lower portion of the door in its opening, said means adapted to break as a result of pressure against the inner face of the door, to permit the release of the door from the opening.

2. The combination with a passage through which material is forced and provided with a door opening in the side thereof, an automatic releasable door mounted in said opening, means for detachably holding the upper portion of the door in position, and breakable means for operatively holding the lower portion of the door in position, whereby as a result of pressure on the inner face of the door the breakable means may be severed and permit the lower portion of the door to disengage from the opening, allowing the upper portion of the door to be automatically released.

3. The combination with the side of a passage through which material passes, of a door fitting said opening, a pair of reinforcing bars connected to the door and having operative automatic detachable connections with the upper part of the casting to assist in holding the door in position, the lower end of one of the bars having a lateral lug, the lower part of the casting having a lateral flange, which together with the lug are provided with registering apertures, of a breakable device engaging said registering apertures and adapted to break as a result of pressure on the inner face of the door, allowing the lower portion of the door to disengage from the door, and thereby permitting an automatic disengagement of the upper ends of the bars from the upper part of the casting.

4. The combination with a passage through which material is forced, including a casting provided with a door opening, said casting having a marginal lateral flange, a reinforcing bar connected to the upper lateral flange and provided with notches, a bar engaging said door opening and provided with a pair of reinforcing bars, the upper ends of which being engageable with said notches, and breakable means operatively connecting the lower end of one of the bars and the lower lateral flange of the casting, and adapted to break as a result of pressure on the inner face of the door, allowing the lower portion of the door to disengage from the opening, and thereby automatically withdraw the upper ends of the bars from the notches, and permitting a release of the door.

In testimony whereof we hereunto affix our signatures.

OSCAR WALTER BRZAZOWSKY.
EVERETT McWILLIAMS.
